ASH-CONVEYING MEANS

James K. Dukas, Edwardsville, Pa.

Application March 3, 1947, Serial No. 731,947

1 Claim. (Cl. 198—224)

1

This invention relates to an ash-conveying means and has for one of its objects the production of a simple and efficient conveyor for automatically removing ashes from the ash-receiving compartment of a furnace to a distant point of disposal.

Other objects and advantages of the present invention will appear throughout the following specification and claim.

In the drawing:

Figure 1 is a fragmentary front elevational view of a furnace illustrating the ash-removing mechanism, the ash-removing housing being shown in longitudinal section;

Figure 2 is a longitudinal sectional view taken on line 2—2 of Figure 1, a portion of the housing being shown in top plan;

Figure 3 is a longitudinal sectional view of a portion of the ash-removing frame;

Figure 4 is a fragmentary sectional perspective view of a portion of the ash-removing frame illustrating the manner of connecting the ends of the blades to the side rails of the frame;

Figure 5 is a perspective view of one of the ash-removing blades.

By referring to the drawing in detail, it will be seen that a housing 41 is illustrated as supporting the furnace 40, the housing 41 extending laterally of the furnace 40, as shown in Figure 1. Thermostats 42 and 43 are suitably located to control the motor 44 which accelerates the driving mechanism of the shaking and grate-operating mechanism. The thermostat 42 is preferably placed adjacent the base of the furnace 40. Trap doors 45 are conveniently located in the top of the housing 41 near the furnace to permit access to the housing 41 adjacent the grate. A grate 46 is supported below the furnace within the housing 41. A shaker grid 47 is slidably mounted over the grate 46 for reciprocating movement. The grid 47 is provided with parallel arms 48 at one end and similar arms 49 at its opposite or formed end. The arms 48 work between the rollers 50 at one end of the housing 41 and the arms 49 work between the rollers 51 at the opposite end the housing 41. Comb rakes 52 and 53 are suspended from the top of the housing 41 at opposite sides of the furnace 40 to prevent large cakes of ashes from passing beyond the grate 46 and falling upon the ash-conveyor mechanism below. These cakes, if any, will be broken-up as the grid reciprocates and the cakes of ashes are thrown against the rakes 52 and 53.

An ash-conveyor means 54 is located below the housing 41.

2

grate 46 and is actuated by links 55 from the operating crank 56, the grid 47 also being actuated simultaneously therewith by suitable links such as the link 57 shown in Figure 2, connected to the crank 56. The crank 56 is driven by the drive mechanism 57 from the motor 47 or other suitable power elements.

It should be noted that the flanged ends 61 fit flat against the transversely spaced upper and lower side rails to brace the ends of the raker plates and to firmly hold the raker plates between the transversely spaced side rails.

The ash conveyor 54 comprises a pair of lower longitudinal side rails 58 which rest upon and are anchored upon the base of the housing 41, and a pair of upper side rails 59 which are slidably mounted on the lower rails 58. The upper rails 59 are connected at one end to the links 55, which links 55 are also connected to the crank 56. These rails 58 and 59 are connected transversely by the raker plates 60. Each raker plate 60 is provided with flanged ends 61. Each flanged end 61 is provided with a longitudinal slot 62. Bracing rods 63 extend transversely between the upper rails 59 and pass through the upper ends of the slots 62 to suspend the raker plates 60 between the rails 59. Pins or other securing elements 64 are located near the upper edges of the lower rails 58 and pass through the slots 62 adjacent the rods 63. As the upper rails 59 are pulled toward the crank 56 or in the direction shown by the arrow in Figure 3, the raker plates 60 will move from a substantially vertical to a substantially horizontal position, and when the plates 60 are returned to a vertical position by the further rotation of the crank 56, the ashes which may have fallen upon the plates 60 or which may be between the adjacent plates will be pushed toward the discharge outlet 65 of the housing 41. As this operation continues, the ashes in the rear will push the forward ashes toward the opening 65 and cause a continuous stream of ashes to be moved longitudinally of the ash conveyor 54. The swinging plates 60 will cause the ashes to be moved longitudinally of the ash conveyor 54 by a pushing and tossing action as the plates 60 swing from a horizontal to a vertical position as the upper rails 59 reciprocate over the lower rails 58. The discharge end 66 is provided with a top gate 67 which may be swung upwardly so that access may be had to the interior of the discharge end 66. An outer end gate 68 is also provided as shown in Figure 1 to facilitate access to the discharge end of the

Having described the invention, what is claimed as new is:

A mechanism of the class described comprising a housing, an ash-conveying means comprising a pair of lower longitudinal transversely spaced side rails, a base supporting said side rails, a pair of upper parallel transversely spaced side rails slidable upon the first mentioned rails, actuating means connected to said upper side rails, a plurality of transversely extending raker plates extending between the transversely spaced side rails, each raker plate having opposite flanged ends fitting flat against the transversely spaced side rails to brace the ends of the raker plates, each flanged end having a longitudinal slot, guiding means carried by the opposite upper rails and extending through the upper ends of said slots to suspend the raker plates between the opposite rails, connecting means located near the upper edges of the opposite lower side rails and passing through said slots to move said raker plates from a substantially vertical to a substantially horizontal position in a swinging movement when the upper side rails are moved longitudinally of the lower rails in one direction and to reverse 25

the movement when the upper side rails are moved longitudinally in the opposite direction.

JAMES K. DUKAS.
